UNITED STATES PATENT OFFICE.

WILLIAM G. AVERY, OF PAINESVILLE, OHIO

METALLIC BARREL.

1,170,036.

Specification of Letters Patent.

Patented Feb. 1, 1916.

Application filed February 27, 1913. Serial No. 751,092.

To all whom it may concern:

Be it known that I, WILLIAM G. AVERY, a citizen of the United States, residing at Painesville, in the county of Lake and State 5 of Ohio, have invented certain new and useful Improvements in Metallic Barrels; and I do hereby declare the following to be a full, clear, and exact description of the invention, such as will enable others skilled 10 in the art to which it pertains to make and use the same.

This invention relates to barrels, casks, kegs or the like containers constructed of metal and has for its object the construction 15 of a metallic barrel, keg or cask of sheet or plate metal, preferably in two parts so that the parts may be nested for shipment and as a further object providing a construction in which the two parts are simply and easily 20 united or assembled with a perfect and strong joint and without the necessity of employing skilled labor or tools for the assemblage.

Other objects will appear as the invention 25 is described and claimed.

This invention consists in the forming of a metal barrel, keg or cask having a joint at the meeting edges of the contiguous sections, said joint composed of a metallic 30 tongue on one of the edges and a metallic groove on the other edge so constructed as to extend practically the whole length of the container so that the tongue or tongues, (where more than two sections are used), 35 will slide snugly into and be held in place by the respective grooves, thus making it necessary only to take the two parts of the container, enter the tongues in the grooves and slide the two parts into position.

40 My invention further consists in other details of construction and combination of parts all of which will be hereinafter fully set forth and claimed.

In the drawings, Figure I, is a cross sectional view of a container embodying this invention, illustrating one manner of constructing the tongue and groove joints and also the employment in connection therewith of trunnions when it is desired to employ the same, and furthermore illustrating a construction of one type of bottom that I intend to employ, this construction allowing for the securing of the sections in the locked position. By constructing the bottom in this manner the same may be folded back when the barrel is unassembled and packed for

shipment. Fig. II, is a vertical cross sectional view taken through a container constructed according to this invention. This view is taken at a right angle to the dividing joint of the halves of the container, showing the joint meeting flush at the interior. This view also illustrates a different type of construction for the bottom. The bottom shown in this view is secured to the respective halves and then the halves are secured to each other when the barrel is assembled. Fig. III, illustrates one form of groove section for the meeting joint, and Fig. IV, represents one form of a tongue joint adapted 70 to register or interlock with the section shown in Fig. III. Fig. V shows both sections united and also shows their relative position on the barrel sections.

It is required in the construction of a 75 metal cask, first that it shall be strong and serviceable, next that it shall be economical to ship and hence should be constructed so that the parts may nest and furthermore the parts should be so constructed that they 80 may be easily and quickly assembled without requiring skilled labor or special tools and with these objects in view I have constructed a barrel which I describe as follows:

In constructing this barrel I employ two metallic sections 1 and 2 of sheet or light plate metal bent to the desired form, preferably semi-cylindrical and having at their meeting edges, on one side a grooved member 3 and on the other side a tongue member 4, the tongue member 4 corresponding with the grooved member 3 of the other section. It is preferred that these tongue and groove members which extend the length 95 of the container at the joint be constructed separate from the sheet metal sections and that they be of a heavier metal, such as, for instance, malleable cast iron and that the same be secured at the meeting edges of the 100 sections by a process known as electrical spot welding. Though this method of attaching the joints to the sheet metal sections is not essential still it is desirable and in preference to other methods now known 105 while at the same time these joints may be fastened to the sheet metal sections in any other desired manner or the tongue and groove may be formed integral and of the same metal as the sections are formed 110 though in the majority of cases this is not as practical or as serviceable.

In constructing and forming the tongue and groove members, if desired, they may be formed, either of them, at the opposite sides of the container with trunnions 5, 5, 5 adapted to be engaged by a suitable barrel truck for transporting the barrels from place to place within or around the shop at which they are employed.

In forming the bottom of the barrel the same may be formed as suggested either in Fig. I, or Fig. II. Fig. I, shows two flanged halves 6 and 7 hinged together as at 8, one of the halves being secured to one section of the barrel and the other half folded upon it when the sections are not assembled, thus allowing for nesting. When the barrel is assembled the loose section is fastened to the other section of the barrel and thus firmly holding the barrel in position. In Fig. II, the bottom is formed of two halves each provided with flanges 9 and 10. The flanges 9 are secured to the respective sections of the barrel and then the flanges 10 are secured together by means of bolts or rivets when the barrel is assembled.

By referring to Figs. I and V, it will be seen that the edges of the sections are so positioned and the tongue and groove members are so located that the sections may be joined together in such a manner as to present a smooth interior surface to the container.

The upper edge of the container may be reinforced by bending the metal upon itself into a hem or hoop, either inward or outward for finish and strengthening purposes.

In illustrating and describing this invention it has been shown and set forth as

it is considered most economical, practical and serviceable but it is not wished to limit the same to the details herein shown as they may be altered in detail and general construction without departing from the invention.

What I claim is:

1. A metallic cask of the type set forth comprising a series of sections, one edge of each section provided with a slotted tubular member and the opposite edge of each section provided with a headed strip, said slotted tubular member and said headed strip adapted to interlock with the headed strip and slotted tubular member of the adjoining section, said slotted tubular member and said headed strip so located as to present a smooth interior surface to said metallic container.

2. A metallic cask of the type set forth comprising a series of sections, each of said sections comprising bottom and side portions of equal proportions, one edge of each side portion provided with a slotted tubular member and the opposite edge of each of said side portions provided with a headed strip adapted to be engaged by the slotted tubular member of the adjoining side portion, said slotted tubular member and said headed strip so located as to present a smooth interior surface to said metallic cask.

Signed at Cleveland in the county of Cuyahoga and State of Ohio this 11th day of February, 1913.

WILLIAM G. AVERY.
